CLAIM

The ornamental design for a fabric hair roller, as shown and described.

DESCRIPTION

FIG. 1 is a perspective front view of a fabric hair roller;
FIG. 2 is a front elevation view of the fabric hair roller;
FIG. 3 is a rear elevation view of the fabric hair roller;
FIG. 4 is a left side elevation view of the fabric hair roller;
FIG. 5 is a right side elevation view of the fabric hair roller;
FIG. 6 is a top plan view of the fabric hair roller;
FIG. 7 is a bottom plan view of the fabric hair roller;
FIG. 8 is a perspective view of the fabric hair roller, shown in use; and,

FIG. 9 is a perspective view of the fabric hair roller, shown in a folded mode.

The broken stitching illustrates a portion of the fabric hair roller. The broken line disclosure of the hair in FIG. 8 illustrates the environment. None of the broken lines forms part of the claimed design.
